United States Patent Office

Des. 223,915

Patented June 20, 1972

223,915

COMBINED DISPENSING NOZZLE AND GUARD THEREFOR

George Z. Brown and William F. Babcock, Akron, Ohio,
assignors to Dover Corporation, Cincinnati, Ohio

Filed Jan. 27, 1970, Ser. No. 21,108

Term of patent 14 years

Int. Cl. D23—01

U.S. Cl. D23—37

FIG. 1 is a perspective view of a combined dispensing nozzle and guard therefor embodying our new design;

FIG. 2 is a perspective view taken on the side opposite that of FIG. 1 of the dispensing nozzle.

FIG. 3 is a top plan view of the dispensing nozzle.

FIG. 4 is a bottom view of the dispensing nozzle.

FIG. 5 is a reduced side elevation thereof.

We claim:

The ornamental design for a combined dispensing nozzle and guard therefor, as shown.
